3 SHEETS—SHEET 3.

UNITED STATES PATENT OFFICE.

FRANK MOTT, OF SHABBONA, MICHIGAN.

SUBMARINE BOAT.

No. 883,040.

Specification of Letters Patent.

Patented March 24, 1908.

Application filed April 20, 1907, Serial No. 369,302. Renewed February 10, 1908. Serial No. 415,164.

To all whom it may concern:

Be it known that I, FRANK MOTT, a citizen of the United States, residing at Shabbona, in the county of Sanilac, State of Michigan, have invented certain new and useful Improvements in Submarine Boats; and I do hereby declare the following to be a full, clear, and exact description of the invention, such as will enable others skilled in the art to which it appertains to make and use the same.

This invention relates to new and useful improvements in life saving attachments for sub-marine boats for use in coast and harbor defenses, and it aims as a primary object to provide means whereby air may be pumped at any time desired into collapsible buoys carried by the boat, when it is desired to raise the same to the surface, especially in cases of emergency and whereby fresh air may be supplied to the crew at any time desired.

The invention aims as a further object to provide a sub-marine boat embodying a novel construction, combination and arrangement of parts, the details of which will appear in the course of the following description, wherein reference is had to the accompanying drawings forming a part of this specification, like characters of reference designating similar parts throughout the several views, wherein:

Figure 1 is a side elevation of a submarine boat and its associated parts, constructed in accordance with the present invention. Fig. 2 is a central vertical transverse sectional view of the body of the boat, showing more particularly the collapsible buoys. Fig. 3 is a central longitudinal section similar to Fig. 2. Fig. 4 is an enlarged side elevation of an automatically controlled air valve and its sustaining means. Fig. 5 is a central longitudinal sectional view of such air valve.

Referring specifically to the accompanying drawings, the numeral 1 designates a cigar-shaped hull or body preferably constructed of metal to afford the required lightness and having its sides curved inwardly for a portion of their depth, as at 2, as shown in Fig. 2, to afford seats for inflatable air bags 3, the latter being sustained by trap doors 4, hinged at their lower edges as at 4', to the hull 1, and overlying the curved sides 2. The doors 4 at their upper edges carry hinged bolts 5, which are projected through stuffing boxes 6 provided in the hull or body 1 and

engaged within said hull or body by retaining nuts or catches 7.

Air is supplied to the hull 1 by means of a flexible hose 8, which at its upper end carries a sectional copper pipe 9 having air openings 10 in its upper portion. The pipe 9 is formed with an internal valve seat 11, through which a stem 12 is projected, said stem at its upper end carrying an air float 13, and at its lower end a valve 14 designed to be raised into engagement with the seat 11. The pipe 9 is fixed to be imposed upon an air tight bag 15 through which the air hose 8 is projected. Within the bag 15, the hose 8 is provided with a check valve 16, for preventing the escape of air from said bag through the hose. A metallic cable 17 depends from the bag 15 and is projected through a stuffing box 18, in a locker 26, into the hull 1. The cable 17 within said hull has its end fixed to a reel 19, rotatable by a crank 20. The air hose 8 when not in use is confined in the locker 26, having a trap door 22, hinged as at 23, to the hull 1 and having bolts 24, projected through stuffing boxes in said hull and engaged by nuts or other fastening means 25. The door 22 is arranged above the locker 26, within which is mounted an air hose reel 27, operated by a crank 28. The locker 26 has a trap door 29 closed by a catch 29', within the hull for a purpose to be described. The reel 27 comprises a hollow shaft having a connection 21 for the air hose 8. The outer end of the shaft or reel 27 is projected through a stuffing box 34 in the locker 26, and has connection by means of a pipe 26' with a manually operated air pump 35 from which leads a conductor 36, having connection with branches 37 leading to the several bags 3 therein. The hull 1 is driven by a propeller 39 operated from an engine (not shown), and is guided by a rudder 40 of conventional form. The cable 17, air hose 8, float 13 and bag 15 are designed to be confined in the locker 26 when the float is not in use. The door 27 of said locker is swung on its hinges to close the same by a chain or cable 42, working through a stuffing box 43.

In operation, it is assumed that the hull has descended beneath the surface of the water and that it is desired to supply fresh air to the crew. In such cases, the trap door 29 is first opened and the operative parts then inspected. The trap door 29 is then closed and held by the catch 29'. The fastenings 25 of the door 22 are then released

and said door is opened by water pressure, the water being pumped into the locker 26 from within the hull by a pump 44 having suitable connections. The float 13 will then rise to 5 the surface closing the valve 14 upon its seat 11 by means of the gravity of the suspended parts. As the float 13 rises it carries the bag 15 therewith and the latter is next inflated by air pumped through the hose 8 from the hull 10 and admitted into the bag 15 through the check valve 16, it being understood that the pump 35 is reversible for such use. The bag 15 when inflated, rises partly above the surface of the water and elevates the float 13, at 15 which time the latter will drop by gravity upon the upper edge of the pipe 9, thus forcing the valve 14 from its seat. The water previously collected in said pipe through the openings 10, will now flow into the hull 20 through the pipe 8 and thus apprise the crew that the parts are ready for use. The pump 35 is now regulated to pump air from the surface of the water through the pipe 8 into the hull, it being understood that the manually 25 controlled cock 41 carried by the conductor 36 within the hull is opened to admit fresh air to the hull. When it is desired to ascend to the surface the pump 35 is regulated to force air through the branches 37 to inflate 30 the bags 3. These bags may be inflated by fresh air from the surface, or by the foul air from the hull admitted through a pipe 36' connected with the cock 41, it being understood that the pump 35 may be regulated accordingly. Prior to inflating the bags 3 it 35 will be understood that the catches 7 are removed from within the hull and that the trap doors 4 are forced outwardly by the bags 3 as they are inflated. When the bags 3 are sufficiently inflated the hull 1 will rise to the sur- 40

face and as said hull rises the reels 19 and 27 are rotated to wind the respective cable 17 and air hose 8 thereupon until the hull reaches the surface.

From the foregoing description it will be 45 seen that simple and efficient means are provided for accomplishing the objects of the invention, but, while the elements herein shown and described are well adapted to serve the functions set forth, it is obvious 50 that various minor changes may be made in the proportions, shape and arrangement of the several parts without departing from the spirit and scope of the invention as defined in the appended claims. 55

What is claimed is:

In a submarine boat, a hull, inflatable air bags carried exteriorly thereof, an air pump, valved connections between said air pump and said air bags, an air hose connected to said pump and projected through said hull, a suspension means therefor comprising an inflatable bag surrounding said hose and having valved communication therewith, and a cable depending from said bag and projected through said hull, a rigid pipe section connected to the upper end of said hose and imposed on said last named bag, said pipe section having air openings in the upper end thereof and an internal valve seat, a stem projected through 65 said valve seat, a valve on the lower end of said stem and a float on the upper end of said stem. 70

In testimony whereof, I affix my signature, in presence of two witnesses.

FRANK MOTT.
